UNITED STATES PATENT OFFICE

VICTOR S. THARP, OF ELMHURST, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

TELEPHONE SYSTEM

Application filed January 23, 1931. Serial No. 510,680.

The present invention relates in general to automatic telephone systems, and its object, broadly stated, is to provide new and improved automatic switching apparatus of the step-by-step type.

More specifically, the object of the present invention is the provision of a new and improved pulsing scheme for positioning automatic switching apparatus.

10 A further object is the provision of a new and improved 200-line connector. The new switch is of the twenty-level type using two sets of wipers; the set to be used is determined by the first digit dialled into the switch.

15 A further object is the provision of a new and improved 200-line frequency selecting connector switch. The first digit dialled into the switch determines the set of wipers, the ringing frequency, and the side of the line over which the ringing current is to be transmitted.

20 A further object is the provision of a new and improved selector circuit performing all necessary and standard operations with four relays instead of the five relays required heretofore.

25 A still further object is the provision of a new busying circuit arranged to signal the calling subscriber to indicate that the line is busy when the connector comes to rest on a busy line. The busy relay is a two-step relay arranged to be energized in its first step to close one set of contacts only when the test wiper of the switch passes over busy lines, and to energize all the way only when the test wiper comes to rest on the busy line.

30 The foregoing objects and features together with others not specifically mentioned at this time will be further discussed in connection with the detailed description of the operation of the various circuits.

35 The accompanying drawings comprising Figs. 1 to 7, inclusive, show by means of the usual circuit diagrams a sufficient amount of equipment in a telephone system embodying the invention to permit it to be readily described and understood. In order for the drawings to be understood best, Fig. 2 should be placed to the right of Fig. 1 with the interconnecting lines in alignment; and Fig. 3

should be placed beneath Fig. 2. Figs. 4, 5, 6, and 7, are schematic drawings showing various methods for wiring the bells to the line for party line ringing. They will be described in connection with Fig. 3.

55 Fig. 1 shows a lineswitch LS, which is one of a plurality of lineswitches controlled by a master switch MS (partially shown) similar to that disclosed in the Voss Patent No. 1,809,086, granted June 9, 1931, and having access to a plurality of selectors, one of which is the selector S. Mechanically, selector S is of the usual vertical and rotary type of switch having its bank contacts arranged in horizontal rows or levels. The selector S has access to a plurality of groups of connectors (ten groups or less), of which connector C, Fig. 2, is one of the connectors in one group, and connector C1, Fig. 3, is one of the connectors in another group. The selector S is 60 of the so-called battery-searching type of switch wherein it must find battery potential over wiper 128 before it will cut in on the idle trunks.

65 Fig. 2 shows a 200-line, 20-level, connector C whose wipers 257-259, inclusive, are used to complete the connection over one set of banks when the wiper switching relay is not energized. The wipers 260-262, inclusive, 70 are used to complete the connection over the other set of banks when the wiper-switching relay is energized.

75 Fig. 3 shows a 200-line, 20-level, frequency selecting connector C1 which is one of the connectors accessible to selector S, Fig. 1, over a particular level. The first digit dialled into the switch operates the auxiliary switch AS to select the ringing frequency to be transmitted to the called subscriber, the side of the line over which the ringing current is to be transmitted, and the set of wipers to be used in establishing the connection.

80 85 Fig. 4 shows two 5-party lines which are accessible to a group of frequency selecting connectors, one of which is connector C1 shown in Fig. 3, over a group of contacts of the second level of their associated bank contacts. Subscribers B1-B5, inclusive, are selectively signalled when the normally con- 90 95 100

connected set of wipers of connector C1 are connected to the party lines and subscribers B6-B10 are selectively signalled when the normally disconnected set of wipers of connector C1 are connected to the party line. The conductors designated FREQ1 to FREQ5, inclusive, all extend to separate ringing current generators similar to generator GEN and the generators are all of different frequencies. The switch jack terminals 1 to 5, inclusive, represent the switch jack terminals of the connector C1, to which the five different ringing generators are connected. The ringers connected to the party lines each respond to a different ringing current frequency, which is in accordance with the well known practice of harmonic signalling.

Fig. 5 shows a 10-party line which is accessible to the same group of frequency selecting connectors as the two 5-party lines shown in Fig. 4, one of which is connector C1 shown in Fig. 3, over a group of contacts of their associated bank contacts. The subscribers C1-C10, inclusive, are all connected to one party line which terminates in the bank contacts which are accessible over the normally connected set of wipers of the connector and are multiplied to the bank contacts which are accessible over the normally disconnected set of wipers. When the normally connected set of wipers are used subscribers C1-C5, inclusive, are selectively signalled and when the normally disconnected set of wipers are used subscribers C6-C10, inclusive, are selectively signalled. The different ringing current generators are wired to the switch jacks of the connector switch as is shown to the left of Fig. 5 which is exactly the same as is shown in Fig. 4. With the party line connectors wired in this manner the same group of switches can be used for selectively signalling both five and ten-party line subscribers.

Fig. 6 shows two 3-party lines which are accessible to a group of frequency selecting connectors having the different ringing current conductors wired to the switch jack terminals of the connectors, as is shown to the left of Fig. 6. For this type of service only three different ringing current frequencies are required.

The three party lines shown in Fig. 6, are accessible to a group of frequency selecting connectors, which are similar to the connector C1 shown in Fig. 3, except that the switch jack terminals of the connectors are wired as shown to the left of Fig. 6. In establishing connections to subscribers D1, D3, and D5 the normally connected set of wipers of the connector is used and in establishing connections with subscribers D6, D8, and D10 the normally disconnected set of wipers is used. It should be noted that for three-party service the ringers of the substations are

bridged across the conductors of the party line.

Fig. 7 shows two 5-party lines which are accessible to the same group of frequency selecting connectors as the two 3-party lines shown in Fig. 6. With the switch jack terminals of this group of frequency selecting connectors wired as is shown to the left of Fig. 7 the five subscribers E1-E5, inclusive, may be selectively signalled when the normally connected set of wipers of any one of the connectors is associated with the bank contacts to which conductors 773 and 775 of the party line are connected and subscribers E6-E10, inclusive, may be selectively signalled when the normally disconnected set of wipers is associated with the bank contacts to which conductors 763 and 765 of the party line are connected. It should be noted that the same group of frequency selecting connectors can be used for selectively signalling subscribers on either 3 or 5-party lines.

The present system, having been described in general, will now be described in connection with a detailed description of the operation of the apparatus shown in the drawings. For this purpose it will be assumed that the subscriber at substation A, Fig. 1, desires to converse with the subscriber at substation A2, Fig. 2, whose telephone number is 3234.

When the receiver is removed at substation A, a circuit is closed across line conductors 11 and 12 for the line relay 14 through contacts of the bridge-cut-off armature 15 of the lineswitch LS. Relay 14 operates and disconnects the so-called private-normal conductor 13 from the bridge-cut-off (upper) winding of the lineswitch magnet 16 and connects it to ground, thereby guarding the calling line against seizure by connectors having access to it. At armature 17 and its front contact, relay 14 closes a circuit for the pull-down (lower) winding of magnet 16 over the associated chain conductor 19 which is grounded at the master switch, and at the same time it opens the chain as regards the succeeding lineswitches. It will be noted that ground potential is supplied to the chain conductor 19 through the contacts of the open chain relay, start relay and lower winding of the delay relay in the master switch MS.

It may be pointed out that the delay relay is included in the circuit to delay the operation of the lineswitch for a slight interval following the operation of the line relay 14. This will give a releasing lineswitch time for the plunger to re-align itself before the lineswitch can be reoperated. The current flow through the pull-down winding over the chain circuit is not sufficient to operate either of the armatures of the magnet 16 as long as the lower winding of the delay relay is in the circuit alone. The upper winding of the delay relay, it will be noted, is normally short-circuited.

cuated through its own contacts. Due to the fact that the short-circuited winding is on the armature end of the relay, it is slow-to-energize. When the delay relay operates, it removes the short circuit from around the upper winding and connects the low resistance upper winding in parallel with the high resistance lower winding, allowing sufficient current to flow over the chain conductor 19 to operate both armatures of the lineswitch magnet 16. The bridge-cut-off armature 15 operates the associated contacts to disconnect ground and line relay 14 from the conductors of the calling line, and the plunger armature 20 operates the bank springs 21-24 and also closes contacts 25. The closing of contacts 25 reconnects the upper winding of magnet 16 to the grounded conductor 13. Line relay 14, being slow-acting, remains operated for an interval.

When the contact springs 21-24 are pressed into engagement with their respective associated contacts to extend the connection to the selector S, the ground potential maintained on conductor 13 by the slow-acting line relay 14 is extended to the release trunk conductor 134 and over the branch conductor 136 to the master switch bank (not shown). Ground on the master switch bank causes the master switch to preselect another idle trunk to a selector similar to selector S.

The lineswitch also completes a circuit at contact springs 21 and 24 and their associated contacts for energizing the line relay 101 of the selector S as follows: From battery, upper winding of line relay 101, armature 121 and its resting contact, conductor 133, contact spring 21 and associated contact of the lineswitch, line conductor 11, subscriber's loop, line conductor 12, contact spring 24 and associated contact of the lineswitch, conductor 135, armature 125 and its resting contact, lower winding of line relay 101, normally closed contacts of overflow springs 130, one side of the dial tone transformer to ground.

Upon energizing, line relay 101, at the normally closed contacts controlled by armature 108, removes the normal shunt around the upper winding of release relay 102 and at the same time it closes a circuit for both windings of release relay 102 in series with the lower winding of series relay 103, from ground, normally closed contacts of the vertical off-normal springs 116, normally closed contacts controlled by armature 112, upper winding of release relay 102, armature 108 and its front contact, lower winding of series relay 103, lower winding of release relay 102, to battery. Release relay 102 energizes over this circuit and at armature 112 and its front contact substitutes a locking ground for the original energizing ground at the vertical off-normal springs 116.

As a further result of its operation, release

relay 102 opens a point in the circuit of the release magnet 107 at armature 110 and its resting contact, at armature 114 and its front contact it prepares a circuit for the rotary magnet, and at armature 113 and its front contact it places ground potential on the release trunk conductor 134 to maintain the lineswitch LS operated through the upper winding of magnet 16 after line relay 14 has fallen back, to busy the calling line in the connector banks over conductor 113, and to busy the trunk to selector S in the master switch bank over conductor 136.

It may be pointed out that the circuit for release relay 102 included the lower winding of series relay 103 which however does not operate. However, when release relay 102 energizes it closes a circuit at armature 111 and its front contact from ground at the normally closed contacts 116 of the vertical off-normal springs VON to the upper winding of series relay 103 and the lower winding of release relay 102 in series. Series relay 103 energizes, due to the current flow over both of its windings, preparing the circuit for the vertical magnet 105 at armature 115 and its front contact and opening a point in the circuit to the rotary magnet 106 at armature 118 and its resting contact.

It should be noted that the original energizing circuit for release relay 102 includes ground at the normally closed contacts of the vertical off-normal spring. It sometimes happens that a selector becomes stuck mechanically and does not restore and consequently the vertical off-normal springs remain in an operated position. Due to the way in which the master switch tests the bank contacts to which the release conductors, similar to release conductor 136, are connected, it will stop on a selector that is not in its normal position, if there is an absence of ground potential on the release conductor thereof. With the selector in an off-normal position it will be seized by a lineswitch such as lineswitch LS. However, when this happens, the release relay 102 does not operate, owing to the fact that the circuit is not completed at the vertical off-normal spring 116 and the lineswitch LS releases for the want of holding potential on conductor 134. The lineswitch will release, and due to the fact that it is a self-aligning lineswitch, the plunger will align itself with the shaft controlled by the master switch and will seize a newly-selected idle trunk to another selector.

The circuit of the line relay 101 includes one side of the dial tone transformer 132, as has been hereinbefore described, and the tone produced by the dial tone current is heard by the calling subscriber, indicating that he may now dial the digits of the desired number.

When the digit 3 is dialled, the circuit of the line relay 101 is opened three times at the

calling station by means of the usual calling device (not shown). Each time the line relay 101 falls back after its circuit is opened, it closes a circuit to the vertical magnet 105 at armature 109 and its resting contact, and opens the circuit including the lower winding of series relay 103 at armature 108 and its front contact. Line delay 101 also places a short circuit around the upper winding of the release relay 102 at the normally closed contacts controlled by armature 108, and by the same action closes a circuit for the upper winding of series relay 103 and the lower winding of the release relay 102 in series as follows: from ground, armature 112 and its front contact, normally closed contacts controlled by armature 108, armature 117 and its front contact, contacts 137 of the vertical off-normal springs VON (closed on the first vertical step), armature 111 and its front contact, upper winding of series relay 103, lower winding of release relay 102, to battery. Series relay 103 remains energized over this circuit. The current flow through the lower winding of release relay 102 is insufficient to keep the relay energized, however, together with the shunt around the upper winding it makes the relay slow to release. The release relay 102 remains energized throughout the series of impulses. Each time line relay 101 energizes following the first deenergization, a circuit is closed to both windings of release relay 102 in series with the upper winding of series relay 103 and both windings of relay 102 in series with the lower winding of series relay 103. Relay 102 is fully energized over this circuit and the amount of current flow over both windings of series relay 103 is insufficient to keep the relay energized, however, it makes the relay slow to release.

By way of an explanation, the first time line relay 101 energizes, release relay 102 also energizes and causes series relay 103 to energize. The first deenergization of line relay 101, during pulsing, causes the vertical magnet to step the wipers up one step, opening contacts 116 and closing contacts 137 of the vertical off-normal springs VON. Line relay 101 also places a shunt around the high resistance upper winding of release relay 102 and by the same action it completes a circuit for the high resistance upper winding of series relay 103 in series with the low resistance lower winding of release relay 102. The shunt around the upper winding and the current flow in the lower winding of relay 102 is just sufficient to keep the relay energized until the line relay is again energized during pulsing to complete the energizing circuit for the release relay. The release relay 102 does not deenergize during pulsing. When the line relay 101 energizes again after the first deenergization, the high and low resistance windings of release relay

102 are included in the circuit of the lower winding of series relay 103 over one path, and the upper winding of series relay 103 in the other path. The amount of current flow in release relay 102 is sufficient to keep the relay energized, but the current flow in series relay 103 is only sufficient to make the relay slow-to-release. The series relay 103 is maintained energized during impulses.

As has been mentioned hereinbefore, the circuit of the line relay 101 has been opened three times by the calling subscriber, and each time a circuit has been completed to the vertical magnet 105. By the operation of the vertical magnet 105 the wipers 127-129 of the selector S are operated step-by-step until they are opposite the third level of the switch bank. The circuit of the line relay 101 and release relay 102 are the same as has been hereinbefore described, and they remain energized. The circuit for each winding of series relay 103 includes both windings of release relay 102 as has been described. In this circuit the current flow in both windings of series relay 103 is only sufficient to make the relay slow to release, and it subsequently restores to normal. Upon restoring to normal series relay 103 opens the part of the circuit of release relay 102 which includes the upper winding of series relay 103 at armature 117 and its front contact, however, release relay 102 remains energized, from ground, armature 112 and its front contact, upper winding of release relay 102, armature 108 and its front contact, lower winding of series relay 103, lower winding of release relay 102, to battery. As a further result of the falling back of series relay 103, the circuit to the vertical magnet 105 is opened at armature 115 and its front contact, and at armature 118 and its resting contact it closes a circuit to the self-interrupting rotary magnet 106. The self-interrupting circuit for the rotary magnet 106 is as follows: from ground, armature 113 and the front contact on release relay 102, contacts 119 of the vertical off-normal springs VON (closed on the first vertical step), armature 114 and its front contact, armature 118 and its resting contact, normally closed contacts 120 of the overflow springs OF, armature 124 and its resting contact, self-interrupting contacts and winding of the rotary magnet 106, to battery. By the buzzer-like operation of the rotary magnet 106, the wipers 127-129 are driven over the contacts of the bank in the third level, or any other level that is selected by the calling subscriber.

When an idle contact set is reached (for example, the contact set from which the conductors 138-140 extend to the connector C), a battery potential is encountered on the test contact thereof by wiper 128, the con-

ductor 139 of connector C being connected to battery through armatures 220, 244, and 256 and their respective resting contacts.

When this battery potential is encountered by test wiper 128, the switching relay 104, whose upper winding is connected between grounded conductor 134 and the test wiper 128, energizes. Upon energizing, relay 104 opens the circuit of the rotary magnet at armature 124 and its resting contact, locks itself over its lower winding in series with the rotary magnet 106 at armature 124 and its front contact from grounded conductor 134, and opens a point in the circuit of the release magnet 107 at armature 122 and its front contact. Relay 104 also extends conductor 134 through to wiper 128 at armature 123 and its front contact, short-circuiting its upper winding at the same time, it disconnects the incoming conductors 133 and 135 from the windings of the line relay 101 at armatures 121 and 125 and extends them through the wipers 127 and 129, conductors 138 and 140, normally closed contacts controlled by armatures 215 and 216, upper and lower windings of line relay 202 of the connector C to battery and ground, respectively.

In case the selector S fails to find an idle trunk line and continues to rotate until the wipers 127-129 pass beyond the last set of bank contacts, contacts 120 and 130 of the overflow springs OF are operated. Contacts 120 of the overflow spring OF open the self-interrupting circuit to the rotary magnet 106 to stop further rotation of the switch, and contacts 130 of the overflow springs OF substitute busy tone current from the busy-tone transformer 131 for the dial-tone current through the dial-tone transformer 132. When the calling subscriber hears the busy-tone from the busy-tone transformer 131, he replaces his receiver. When this occurs line relay 101 falls back and places a shunt around the upper winding of release relay 102 at the normally closed contacts controlled by armature 108. Due to the shunt around its upper winding, release relay 102 is made slow to release, and subsequently restores to normal. Upon falling back, release relay 102 closes a circuit to the release magnet 107 from ground, armature 110 and its resting contact, armature 122 and its resting contact, contacts 126 of the vertical off-normal springs VON (closed on the first vertical step), winding of release magnet 107, to battery. Release magnet 107 energizes and the switch restores to its normal position. The lineswitch LS releases in the usual manner when the ground potential is removed from conductor 134.

When the 20-level connector C is seized by the selector S over conductors 138 and 140, line relay 202 energizes over the previously traced circuit. Upon energizing, line relay 202 removes the shunt around the upper

winding of release relay 203 at the normally closed contacts controlled by armature 217 and at the same time it closes a circuit for both windings of the release relay 203 in series with the lower winding of series relay 204, from ground, upper winding of release relay 203, armature 217 and its front contact, lower winding of series relay 204, lower winding of release relay 203, to battery. Release relay 203 energizes over this circuit and at armature 222 and its front contact it closes a circuit for the upper winding of series relay 204 in series with both of its windings. However, due to the fact that the high resistance upper winding of release relay 203 is in series with both of the windings of series relay 204, it does not energize.

As a further result of its operation release relay 203 opens a point in the circuit of the release magnet 210 at armature 219 and its resting contact, at armature 223 and its front contact it prepares the impulsive circuit, and at armature 220 and its front contact it places ground potential on the release trunk conductor 139 to maintain the switch through relay 104 of the selector S energized after the subsequent release of the release relay 102 due to the deenergization of the line relay 101, and also to maintain the ground potential on the release trunk conductor 134. This switch is now prepared for dialling.

The calling subscriber now manipulates the calling device in accordance with the second digit in the telephone number of the wanted subscriber. When the second digit is dialled, which in this case is the digit 2, the circuit of the line relay 202 is opened two times at the calling station. Each time the line relay 202 falls back it places a short circuit around the upper winding of release relay 203 at the normally closed contacts controlled by armature 217, and by the same action it closes a circuit for the upper winding of series relay 204 in series with the lower winding of release relay 203 as follows: from ground, normally closed contacts controlled by armature 217, armature 222 and its front contact, upper winding of series relay 204, lower winding of release relay 203, to battery. Series relay 204 energizes over this circuit. The current flow through the lower winding of release relay 203 is insufficient to keep the relay energized, however, together with the shunt around the upper winding the relay is made slow-to-release. The release relay 203 remains energized throughout the series of impulses.

Each time line relay 202 energizes following the first deenergization, a circuit is closed to both windings of release relay 203 in series with the upper winding of series relay 204 and both windings of release relay 203 in series with the lower winding of series relay 204. Release relay 203 is fully energized again over this circuit. The current flow over both windings of series relay 204 is in-

sufficient to keep the relay energized however, enough current flows to make the relay slow-to-release. Series relay 204 remains energized during each series of impulses, but 15 subsequently deenergizes after the line relay remains in an energized position.

By way of an explanation, the first time line relay 202 is energized, release relay 203 is also energized. The first time line relay 202 10 deenergizes, during impulsing, series relay 204 energizes. Release relay 203 and series relay 204 both remain operated during the series of impulses. After impulsing, line relay 202 remains in its energized position, release relay 203 remains energized, and series relay 204 subsequently deenergizes.

The first time line relay 202 falls back, during impulsing, it closes a circuit from ground, armature 218 and its resting contact, 20 armature 223 and its front contact, armatures 241, 249, and 230 and their respective resting contacts, contacts 235 of the vertical off-normal springs VON, armature 236 and its resting contact, lower winding of two-step relay 25 206, to battery. Two-step relay 206 energizes in its first step, closing contacts A only, to prepare a locking circuit for itself from ground at armature 221 and its front contact. It is obvious that the upper winding 30 of two-step relay 206 is short-circuited by its initial energizing circuit and it cannot operate to its second step until the short circuit is removed. Line relay 202 subsequently energizes again as has been described hereinbefore, and opens the initial energizing circuit 35 for two-step relay 206 at armature 218 and its resting contact. The opening of the original energizing circuit for two-step relay 206 removes the short circuit from its upper winding, permitting the relay to energize to its 40 second step over both windings in series to close all of its armatures from ground, armature 221 and its front contact, contacts A of relay 206, both windings of relay 206, to battery. Upon energizing to its second step, relay 206 prepares a circuit for combination 45 switchover and ring-cut-off relay 205 at armature 233 and its front contact, it prepares a circuit for the wiper-switching relay 209 at armature 236 and its front contact, and it 50 prepares a locking circuit for relay 209 at armature 237 and its front contact.

The second time line relay 202 falls back, it again closes armature 218 and its resting 55 contact to complete a circuit over the path just traced. This time the two-step relay 206 is energized and the circuit includes armature 236 and its front contact, normally closed contacts controlled by armature 254, 60 winding of wiper-switching relay 209, to battery. The wiper switching relay 209 energizes and locks itself at armature 254 and its front contact to ground at armature 237 and its front contact, and by the same action it 65 opens its initial energizing circuit from

ground at armature 218. The wiper-switching relay 209 also connects up wipers 260-262 at armatures 252, 253, and 255 and their respective front contacts.

After the first series of impulses has been 70 transmitted, line relay 202 remains in an energized position. Series relay 204 subsequently releases, as has been hereinbefore described. Upon falling back, series relay 204 completes a circuit for the slow-acting combination switchover and ring-cut-off relay 205 from ground, armature 226 and its resting contact, contacts 227 of the vertical off-normal springs VON, armature 233 and its front contact, lower winding of relay 205, to 80 battery. Upon energizing, relay 205 prepares a locking circuit for itself at armature 229 and its front contact and it prepares the circuit for the vertical magnet 211 at armature 230 and its front contact. The closing 85 of armatures 228 and 231 and their respective front contacts has no effect at this time.

The calling subscriber may now dial the third digit of the called number. When the third digit is dialled, which is in this case 90 the digit 3, the circuit of the line relay 202 is again intermittently interrupted three times in response to the operation of the calling device by the calling subscriber. The first time line relay 202 falls back, series relay 204 95 energizes and remains in an energized position throughout the series of impulses as has been hereinbefore described. Upon energizing, series relay 204 opens the initial energizing circuit for the slow-acting combination switchover and ring-cut-off relay 205 at armature 226 and its resting contact, however, it also completes a locking circuit for 100 relay 205 before it falls back from ground, armature 226 and its front contact, armature 229 and its front contact, lower winding of 105 relay 205, to battery. As a further result of the falling back of line relay 202 a circuit is completed for the vertical magnet 211, from ground, armature 218 and its resting contact, armature 223 and its front contact, armatures 241 and 249 and their respective resting contacts, armature 230 and its front contact, winding of the vertical magnet 211, to battery. Each time the line relay 202 falls back 110 the circuit is completed to the vertical magnet 211 and by its operation the wipers 257-262, inclusive, are raised opposite the third level of bank contacts.

At the end of the vertical movement, the 115 line relay remains energized and series relay 204 subsequently releases as has been described. Upon falling back, series relay 204 opens the locking circuit for the combination switchover and ringcutoff relay 205 at armature 226 and its front contact. Relay 205 subsequently releases due to the fact that its initial energizing circuit has been opened, by the first vertical step of the switch, at contacts 227 of the vertical off-normal springs 120

VON. Upon the falling back, relay 205 prepares the circuit for the rotary magnet 212 at armature 230 and its resting contact.

The calling subscriber now transmits the final digit of the called telephone number, which is in this case the digit 4. Responsive to the interruptions of the line relay 202, series relay 204 is energized again and remains energized throughout the series of impulses. Each time line relay 202 falls back a circuit is completed for the rotary magnet 212 from ground, armature 218 and its resting contact, armature 223 and its front contact, armatures 241, 249, and 230 and their respective resting contacts, contacts 234 of the vertical off-normal springs VON (closed on the first vertical step of the switch), winding of the rotary magnet 212, to battery. By the operation of the rotary magnet the wipers 257-262, inclusive, are rotated step-by-step and are finally brought to rest in engagement with the particular set of bank contacts in which the line of substation A2, whose telephone number is 8234, is terminated.

The series relay 204, in its operated position, connects the test wiper 261 to the two-step busy test relay 207. If any of the contacts the test wiper 261 passes over are busy, the conductor similar to conductor 264 is grounded, causing the two-step busy test relay 207 to be energized to its first step from ground (over a conductor similar to conductor 264), test wiper 261, armature 253 and its front contact, normally closed contacts controlled by armature 245, normally closed contacts controlled by armature 239, armature 225 and its front contact, armature 246 and its resting contact, resistance 232, winding of relay 207, to battery. This relay is only momentarily operated to its first step and closes contact A at armature 240 only as the test wiper 261 passes over contacts of the busy lines. The operation of the relay to its first step has no effect at this time because the circuit for energizing the relay to its second step is opened at the normally closed contacts controlled by armature 225 of the series relay 204.

The final digit has now been received and the wipers of the connector have been placed in connection with the terminals of the called line. If the line is busy, there will be a ground potential on the test conductor 264 and the above circuit is again completed for operating the busy test relay 207 to its first step before the series relay 204 falls back. Series relay 204 subsequently releases however, and at the normally closed contacts controlled by armature 225 it completes a circuit for energizing the busy test relay to its second step, from grounded conductor 264, wiper 261, armature 253 and its front contact, normally closed contacts controlled by armatures 245, 239, and 225, armature 240 and its front contact A, winding of relay 207, to bat-

tery. Upon energizing to its second step the busy test relay 207 opens the circuit for the rotary magnet 212 at armature 241 and its resting contact to prevent further rotation of the wipers, locks itself to grounded conductor 139 at armature 239 and its front contact, at the same time opening its initial energizing circuit over the test wiper and it connects the busy tone conductor to the upper side of the line at armature 238 and its front contact. The subscriber, upon hearing the busy signal, will replace his receiver, thereby releasing the connector C and all previously operated switches.

Assuming now that the called line is idle when the connection is established, under these circumstances there will be no ground on conductor 264 and consequently the busy relay 207 will not be energized. Shortly after the last impulse of the series the series relay 204 falls back and completes the circuit for the slow-acting switching relay 208 from grounded conductor 139, armature 239 and its resting contact, lower winding of switching relay 208, armature 240 and its resting contact, normally closed contacts controlled by armatures 225, 239, and 245, armature 253 and its front contact, test wiper 261, conductor 264, and thence to battery by way of the bridge-cut-off winding of the lineswitch magnet of the associated lineswitch (not shown), which lineswitch may be the same as the lineswitch LS associated with the line of substation A. Responsive to the closure of this circuit the lineswitch magnet of the called lineswitch operates its bridge cut-off armature to disconnect the line relay of the lineswitch from across the line conductors thereat.

In the connector C the slow-acting switching relay 208 energizes over the above-traced circuit and at its lightly adjusted armature 247 closes a locking circuit for its upper winding, opens the circuit for the rotary magnet 212 at armature 249 and its resting contact, and places direct ground on the test wiper at armature 245 and its front contact and by the same action opens its initial energizing circuit. Relay 208 also prepares a locking circuit for the combination switch-over and ring-cut-off relay 205 at armature 248 and its front contact, connects the ring-back tone conductor to the calling line at armature 242 and its front contact to indicate to the calling subscriber that the calling line is being signalled, and it connects up the line wipers 260 and 262 at armatures 243 and 251 and their respective front contacts. By the latter operation, a signalling circuit is established whereby ringing current from the generator GEN is intermittently projected over the called line to operate the bridged ringer at substation A2 to notify the called subscriber that he is wanted. The return path for the ringing current includes the upper winding of the combina-

tion switchover and ring-cut-off relay 205 and ground.

When the called subscriber responds to the ringing of his bell by removing his receiver, a direct current bridge is closed across the associated line conductors 263 and 265 in the regular manner, whereupon the ring-cut-off relay 205 energizes.

Upon energizing, the combination switch-over and ring-cut-off relay 205 closes a locking circuit for itself at its lightly adjusted armature 229, disconnects the line wipers from its own upper winding and the generator lead at armatures 228 and 231 and their respective resting contacts, opens the ring-back tone circuit for the calling subscriber at the normally closed contacts controlled by armature 228, and it completes the talking connection at armatures 228 and 231 and their respective front contacts.

Current is now supplied to the transmitter at substation A2 through the windings of the double-wound back bridge relay 201, which is accordingly energized. This relay is reversing relay and has the well-known function of reversing the incoming trunk conductors 138 and 140, as regards their connections with the windings of relay 202. Relay 201 opens a point in the circuit for the release magnet 210 at armature 213 and its resting contact, and at armature 214 and its front contact closes an additional holding circuit for relays 206 and 208. The reversing of the line conductors 138 and 140 is a standard operation, and is for the purpose of operating a subscriber's pay-station or metering apparatus, and in some cases is used for supervisory purposes. The desired connection is now completed and the subscribers may converse as desired.

When the conversation is completed the two subscribers replace their receivers. Should the calling subscriber restore his receiver first, the line relay 202 will deenergize and open the circuit of the slow-release relay 203. Relay 203 subsequently deenergizes and removes the ground from conductor 139 at armature 220 and its front contact, releasing the preceding switches in the usual manner. The connector C does not release due to the fact that the circuit for the release magnet 210 is open at armature 213 and its resting contact. The connector cannot be seized by any selector, such as selector S, because the battery potential is disconnected from conductor 139 at armature 244 and its resting contact. When the called subscriber hangs up his receiver, relay 201 deenergizes, removes the locking ground for relays 206 and 208 at armature 214 and its front contact, and closes a circuit for the release magnet 210 at armature 213 and its resting contact. Relay 206 deenergizes and opens a point in the locking circuit for wiper-switching relay 209. The slow-to-release switch-through re-

lay 208 subsequently falls back. Upon restoring to normal, switch-through relay 208 opens the locking circuit for the wiper-switching relay 209 at armature 250 and its front contact, removes the locking ground for the combination switch-over and ring-cut-off relay 205 at armature 248 and its front contact, places battery potential on conductor 139 at armature 244 and its resting contact, removes the ground potential from the test wiper at armature 245 and its front contact, and opens the speaking connection at armatures 243 and 251 and their respective front contacts. The wiper-switching relay 209 deenergizes and connects up the normally connected wipers. The combination switch-over and ring-cut-off relay 205 subsequently falls back and the switch is restored to its normal position. The switch-through relay 208 is made slow-to-release to prevent the wiper-switching relay from releasing and connecting up the normally connected wipers before the switch shaft has restored the wipers to their normal position. If the called party hangs up first the connector C is then released under control of the calling party.

It will be assumed that the calling subscriber desires to establish a connection with substation A1, whose telephone number is 3134. The setting up of the connection is exactly the same as described in establishing a connection with substation A2 whose telephone number is 3234, except that the second digit dialled is a 1 instead of a 2. The first digit (1) dialled into the connector (the second digit of the telephone number), locks up two-step-relay 206 as before. In this case only one impulse is transmitted; therefore, the wiper-switching relay 209 is not energized. The connection is then completed as previously described, but in this case over the normally connected wipers of the switch.

It can be readily seen that the first digit (1 or 2) dialled into the connector C selects the set of wipers over which the connection is to be established.

A detailed description of the operation which takes place when the subscriber at substation A calls the party line subscriber B6, shown in Fig. 4, whose telephone number is 2634 will now be given. When the calling subscriber removes his receiver and dials the digit 2 the operation of the lineswitch LS and the selector S is exactly the same as described hereinbefore, except that the wipers 127-129, inclusive, of the selector S are positioned to the second level of the selector bank contacts to engage the bank contacts to which the conductors 141-143, inclusive, are connected.

In response to the seizing of connector C1 over the line conductors 141 and 143, the line relay 302 and the release relay 303 are energized. The operation of the line relay 302, release relay 303 and series relay 304,

is the same as described in connection with line relay 202, release relay 203 and series relay 204 in the connector C, shown in Fig. 2 of the drawings.

5 The calling subscriber may now dial the second digit of the called number which in this case is assumed to be the digit 6. Each time line relay 302 falls back, responsive to the opening of its circuit by the dial at the calling subscriber's telephone, a circuit is closed from ground, armature 318 and its resting contact, armature 323 and its front contact, armatures 341, 349 and 330 and their respective resting contacts, normally closed 10 contacts 335 of the vertical off-normal springs VON, winding of magnet 368 of the auxiliary switch AS, to battery. In response to the six impulses over this circuit the wipers 371 and 372 of the auxiliary switch AS are advanced step-by-step to the sixth contacts of their respective banks. At the end of the 15 series of impulses, series relay 304 deenergizes and completes a circuit from battery, lower winding of the combination switch-over and ring-cut-off relay 305, normally closed contact 327 of the vertical off-normal springs VON, armature 326 and its resting contact, wiper 371 and the sixth bank contact of the auxiliary switch AS, upper winding of the reversing relay 306, upper winding of wiper switching relay 309, armature 321 and its front contact, to ground. Relays 305, 306, and 309 energize over the above circuit. Upon energizing, relay 306, at its lightly adjusted armature 333, closes a locking circuit for itself from battery, resistance 366, armature 333 and its front contact, lower winding of relay 306, armature 321 and its front contact, to ground. At armatures 336 and 337 20 and their respective front contacts, relay 306 prepares the circuit for transmitting ringing current over the lower line conductor. Upon energizing, the wiper switching relay 309 closes a locking circuit for itself at its lightly adjusted armature 354, from battery, lower winding of relay 309, armature 354 and its front contact, normally closed contacts controlled by armature 350, armature 321 and its front contact, to ground. At armatures 352, 353, and 355 and their respective front contacts, relay 309 connects up the normally disconnected wipers 360-362, inclusive. The combination switch-over and ring-cut-off relay 305, upon energizing, prepares a locking 25 circuit for itself at armature 329 and its front contact, and it also prepares the circuit for the vertical magnet 311 at armature 330 and its front contact. The closing of armatures 328 and 331 and their respective front contacts has no effect at this time.

The calling subscriber may now dial the third digit of the called number. When the third digit is dialled, which in this case is the digit 3, the circuit of the line relay 302 is again intermittently interrupted three times

in response to the operation of the calling device by the calling subscriber. The first time line relay 302 falls back, series relay 304 energizes and remains in an energized position throughout the series of impulses as has 30 been hereinbefore described. Upon energizing, series relay 304 opens the initial energizing circuit for the slow-acting combination switch-over and ring-cut-off relay 305 at armature 326 and its resting contact and by the 35 same action it also completes a locking circuit for relay 305 before it falls back, from battery, lower winding of relay 305, armature 329 and its front contact, normally closed contacts controlled by armature 348, armature 326 and its front contact over the previously traced circuit which includes the upper windings of relays 306 and 309, respectively, to ground at armature 321 and its front contact. As a further result of the falling back 40 of line relay 302 a circuit is completed for the vertical magnet 311, from ground, armature 318 and its resting contact, armature 323 and its front contact, armatures 341 and 349 and their respective resting contacts, armature 330 and its front contact, winding of the vertical magnet 311, to battery. Each time the line relay 302 falls back this circuit is completed to the vertical magnet 311. By the operation of the vertical magnet 311, the 45 wipers 357-362, inclusive, are raised opposite the third level of the bank contacts.

At the end of the series of impulses, the line relay 302 remains energized and series relay 304 subsequently releases as before. Upon falling back, series relay 304 opens the locking circuit for the combination switch-over and ring-cut-off relay 305 at armature 326 and its front contact. Relay 305 subsequently releases due to the fact that its initial energizing circuit has been opened at contacts 50 327 of the vertical off-normal springs VON on the first vertical step of the switch. Upon falling back, relay 305 prepares a circuit for the rotary magnet 312 at armature 330 and its 55 resting contact.

The calling subscriber now transmits the final digit of the called telephone number, which is in this case the digit 4. Responsive to the interruptions of the line relay 302, series relay 304 is energized again and remains energized throughout the series of impulses. Each time line relay 302 falls back a circuit is completed for the rotary magnet 312 from ground, armature 318 and its resting contact, armature 323 and its front contact, armatures 341 and 349 and their respective resting contacts, armature 330 and its resting contact, contacts 334 of the vertical off-normal springs VON (closed on the first 60 vertical step of the switch), winding of the rotary magnet 312, to battery. By the operation of the rotary magnet 312 the wipers 357-362, inclusive, are rotated step-by-step and are finally brought to rest in engagement 65

with the particular set of bank contacts to which the line of substation B6, whose telephone number is 2635, is terminated.

The series relay 304 in its operated position connects the test wiper 361 to the two-step-busy-test relay 307. If any of the contacts the test wiper 361 passes over are busy, the conductor similar to conductor 364 is grounded, causing the two-step-busy relay 307 to be energized in its first step from 10 ground (over a conductor similar to conductor 364), test wiper 361, armature 363 and its front contact, normally closed contacts controlled by armature 345, normally closed contacts controlled by armature 339, armature 325 and its front contact, armature 346 and its resting contact, resistance 332, winding of relay 307, to battery. This relay is only momentarily operated to its first step and closes contact A at armature 340 only, as 15 the test wiper 361 passes over contacts of the busy lines. The operation of the relay to its first step has no effect at this time because the circuit for energizing the relay to its second step is opened at the normally 20 closed contacts controlled by armature 325 25 of the series relay 304.

The final digit has now been received and the wipers of the connector have been placed in connection with the terminals of the called 30 line. If the line is busy, there will be a ground potential on the test conductor 364, completing the circuit again for operating the busy-test relay 307 to its first step as described above before the series relay 304 falls back. Series relay 304 subsequently releases, 35 however, and at the normally closed contacts controlled by armature 325 it completes a circuit for energizing relay 307 to its second step, from grounded conductor 364, test wiper 361, armature 353 and its front contact, normally closed contacts controlled by armatures 345 and 339, respectively, normally closed contacts controlled by armature 325, armature 340 and its front contact A, winding of relay 307, to battery. Upon energizing to its second step the busy-test relay 40 307 opens the circuit for the rotary magnet 312 at armature 341 and its resting contact to prevent further rotation of the wipers, locks itself at armature 339 and its front contact to ground at armature 321 and its front contact, at the same time opening its initial 45 energizing circuit over the test wiper 361, and it connects the busy tone conductor to the upper line conductor at armature 338 and its front contact. The subscriber, upon hearing the busy signal, will replace his receiver, thereby releasing the connector C1 and all 50 55 previously operated switches.

Having explained the operation which takes place when the called line is busy it will now be assumed that the called line is idle when the connection is established.

60 Under these circumstances there will be no

70 ground on conductor 364 and consequently the busy test relay 307 will not be energized. Shortly after the last impulse of the series the series relay 304 falls back and completes the circuit for the slow-acting switching relay 308 from ground, armature 321 and its front contact, armature 339 and its resting contact, upper winding of switching relay 308, armature 367 and its resting contact, normally closed contacts controlled by armatures 325, 339, and 345, respectively, armature 353 and its front contact, test wiper 361, conductor 364, and thence to battery by way of the bridge cut-off winding of the lineswitch magnet of the associated lineswitch (not shown), which lineswitch may be the same as the lineswitch LS associated with the line of the substation A. Responsive to the closure of this circuit the lineswitch magnet of the called lineswitch operates its bridge-cut-off 80 armature to disconnect the line relay of the lineswitch from across the line conductors 85 thereof.

90 In the connector C1 the slow-acting switching relay 308 energizes over the above traced circuit and at its lightly adjusted armature 347 closes a locking circuit for its lower winding from ground at armature 321 and its front contact, opens the circuit for the rotary magnet 312 at armature 349 and its resting contact, and places direct ground on the test wiper 361 at armature 345 and its front contact, and by the same action opens its initial 95 energizing circuit. Relay 308 also prepares a locking circuit for the combination switch-over and ring-cut-off relay 305 at armature 348 and its front contact, connects the ring-back-tone conductor to the calling line at armature 342 and its front contact to indicate to the calling subscriber that the calling line is being signalled, and it connects up the line wipers 360 and 362 at armatures 343 and 351 and their respective front contacts. By the latter operation, a signalling circuit is established whereby ringing current from conductor FREQ. 3 is intermittently projected over the called line to operate the ringer at the substation B6 to notify the called subscriber that he is wanted. The signalling circuit for the called subscriber is 100 as follows: From the battery connected generator GEN, ringing interrupter RING INT., conductor FREQ. 3 connected to switch jack 3 of the connector, sixth contact of the bank associated with wiper 372, wiper 372, upper winding of the combination switch-over and ring-cut-off relay 305, armature 336 and its front contact, armature 331 and its resting contact, armatures 351 and 105 355 and their respective front contacts, wiper 362, conductor 365, and the ringer at substation B6, to ground. The above circuit is intermittently opened and closed by the 110 operation of the ringing interrupter RING INT. and the ringer at substation B6 is thus 115 120 125 130

operated at intervals to signal the called subscriber. It is understood, of course, that the ringing current also flows through the ringers at substation B8 and B10, to ground at the same time, but the ringers thereat are tuned so that they will not respond to the frequency of the ringing current which is now in use. This is according to the well known practice of harmonic signalling, and it follows that the ringer at substation B6 is the only one which is operated.

When the called subscriber at substation B6 removes his receiver to answer the call, the ringer thereat is disconnected and the 15 ringing circuit is completed over a circuit including the other line conductor 363, wiper 360, armature 352 and its front contact, armature 343 and its front contact, armature 328 and its resting contact, armature 337 and its front contact, to ground. The combination 20 switch-over and ring-cut-off relay 305 energizes over this circuit and closes a locking circuit for itself at its lightly adjusted armature 329 and its front contact, from ground 25 at armature 348 and its front contact, through the lower winding of relay 305 to battery. Relay 305 also opens its original energizing circuit at armatures 328 and 331 and their respective resting contacts and at the same time 30 completes a talking connection at their respective front contacts, and by the same action disconnecting the ring-back-tone conductor from the upper line conductor 141.

Current is now supplied to the transmitter 35 at substation B6 through the windings of the double wound back-bridge relay 301, which is accordingly energized. This relay is a reversing relay and has the well known function of reversing the incoming trunk conductors 141 and 143, as regards their connections with the windings of line relay 302. Relay 301 opens a point in the circuit for release magnet 310 at armature 313 and its resting contact, and at armature 314 and its front 40 contact closes an additional holding circuit for relays 306 and 308. The reversing of the line conductors 141 and 143 is a standard operation, and is for the purpose of operating a subscriber's paystation or metering apparatus, and in some cases is used for supervisory purposes. The desired connection is now completed and the subscribers may converse as desired.

When the conversation is completed the 45 two subscribers replace their receivers. The releasing of the connection is controlled by the calling and the called subscriber in the same manner as described in connection with the connector C shown in Fig. 2. However, an additional circuit is provided under the control of release relay 303 which is closed when the calling subscriber hangs up his receiver to restore the auxiliary switch AS to its normal position. The circuit for releasing 50 the auxiliary switch AS is as follows: ground,

armature 371 and its resting contact, off-normal springs 369 of the auxiliary switch AS (closed on the first rotary step of its wipers 371-372), winding of the release magnet 370 of the auxiliary switch AS, to battery. All 70 the apparatus used in establishing a connection is thus released and may be used in the establishment of another connection.

An explanation will now be given of the manner in which connections are established with the other four substations on this party line. The substations B7, B8, B9, and B10, shown in Fig. 4, may be reached by dialling 2734, 2834, 2934, and 2034, respectively. It 75 will be noted that the first, third, and fourth 80 digits of the telephone numbers are exactly the same as used in calling substation B6.

When the digit 7 is dialled for the second digit of a telephone number the combination switch-over and ring-cut-off relay 305 and the wiper switching relay 309 are energized in series over the previously described circuit which now includes the seventh bank contact associated with wiper 371. It will be noted that relay 306 is not in this circuit, therefore, 85 FREQ. 4 will be transmitted over the upper line conductor to subscriber B7 whose ringer is shown connected to the upper line conductor 363, Fig. 5.

Should the calling subscriber desire to converse with the substation B8 the second digit of the telephone number would be the digit 8. In this case the wipers 371-372 of the auxiliary switch AS are advanced to the eighth bank contact. The operation of the switch in this case will be exactly the same as described in connection with a call for substation B6, except that FREQ. 4 is transmitted over the lower line conductor to subscriber B8 whose ringer is shown connected to the lower line conductor 365, Fig. 4.

In establishing a connection to substation B9 or B10 the second digit of the telephone number would be either 9 or 0. If substation B9 is dialled the wipers 371-372 of the auxiliary switch AS are advanced to the ninth bank contact. The operation of the circuit in this case is exactly the same as disclosed in connection with the description of establishing a connection with substation B7, 100 except in this case FREQ. 5 is transmitted over the upper line conductor to subscriber B9 whose ringer is shown connected to the upper line conductor 363, Fig. 4.

In establishing a connection to substation B10 the wipers of the auxiliary switch AS are advanced to the tenth bank contact when the digit 0 is dialled. The operation of the circuit in this case is the same as described in connection with establishing a connection 110 with substations B6 and B8, respectively, except in this case FREQ. 5 is transmitted over lower line conductor to subscriber B10 whose ringer is shown connected to the lower line conductor 365, Fig. 4.

An explanation will now be given of the manner in which a connection is established with substation B5, as shown in Fig. 4. The substation B5 may be reached by dialling 2534 and it will be noted that the first, third and fourth digits of the telephone number are exactly the same as used in calling substations B6-B10, inclusive. When a calling subscriber removes his receiver and dials the digit 2 the operation of the lineswitch LS and the selector S, shown in Fig. 1, is exactly the same as described hereinbefore. The connector C1 is seized in the regular manner over conductors 141 and 143, operating the line relay 302 and the release relay 303, as has been described.

The calling subscriber may now dial the second digit of the called number, which in this case is assumed to be the digit 5. Each time the line relay 302 falls back a circuit is closed to magnet 368 of the auxiliary switch AS. In response to the five impulses magnet 368 advances its wipers 371 and 372 to the fifth contacts of their respective banks. At the end of the series of impulses, series relay 304 deenergizes as before and completes a circuit from battery, lower winding of the combination switch-over and ring-cut-off relay 305, normally closed contacts 327 of the vertical off-normal springs VON, armature 326 and its resting contact, wiper 371 and the fifth bank contact of the auxiliary switch AS, armature 321 and its front contact to ground. The combination switch-over and ring-cut-off relay 305 energizes over the above circuit and prepares a locking circuit for itself at armature 329 and its front contact, and at armature 330 and its front contact prepares a circuit for the vertical magnet 311. The closing of armatures 328 and 331 and their respective front contacts has no effect at this time.

The calling subscriber may now dial the third and fourth digits of the called number. When the third and fourth digits are dialled, which in this case are the digits 3 and 4, respectively, the wipers 357-362 are raised opposite the third level of the bank contacts by the operation of the vertical magnet 311, and are rotated in to the fourth bank contacts by the operation of the rotary magnet 312, as has been hereinbefore described.

It should be noted at this time that the wiper switching relay 309 has not been operated, therefore, the connection will be established over the normally connected set of wipers 357-359, respectively. The final digit has now been received and the wipers of the connector have been placed in connection with terminals of the called line. If the line is busy, there will be a ground potential on the test conductor 374, which completes a circuit for operating the two-step busy-test relay 307 to its first step before the series relay 304 falls back after the series

of impulses. Series relay 304 subsequently releases, however, and at the normally closed contacts controlled by armature 325 it completes a circuit for energizing relay 307 to its second step, from grounded conductor 374, test wiper 358, armature 353 and its front contact, normally closed contacts controlled by armatures 345, 339, and 325, respectively, armature 340 and its front contact A, winding of relay 307, to battery. Upon energizing to its second step the busy test relay 307 opens the circuit for the rotary magnet 312 at armature 349 and its resting contact to prevent further rotation of the wipers, locks itself at armature 339 and its front contact to ground at armature 321 and its front contact, and at the same time opens its initial energizing circuit over the test wiper 358, and it connects the busy tone conductor to the upper line conductor at armature 338 and its front contact. The calling subscriber, upon hearing the busy signal, will replace his receiver thereby releasing the connector C1 and all previously operating switches.

Having explained the operation which takes place when the called line is busy it will now be assumed that the called line is idle when a connection is established. Under these circumstances there will be no ground on conductor 374 and the two-step-busy-test relay 307 will not be energized. Shortly after the last impulse of the series, the series relay 304 falls back and completes the circuit for the slow-acting switching relay 308 from ground, armature 321 and its front contact, armature 339 and its resting contact, upper winding of the switching relay 308, armature 367 and its resting contact, normally closed contacts controlled by armatures 325, 339, and 349, respectively, armature 353 and its front contact, test wiper 358, conductor 374, and thence to battery by way of the bridge-cut-off winding of the lineswitch magnet of the associated lineswitch (not shown), which lineswitch may be the same as the lineswitch LS associated with the line at the substation A, shown in Fig. 1. Responsive to the closure of this circuit the lineswitch magnet of the called lineswitch operates its cut-off armature to disconnect the line relay of the lineswitch from across the line conductors thereat.

In the connector C1 the slow-acting switching relay 308 energizes over the above traced circuit and at its lightly adjusted armature 347 closes a locking circuit for its lower winding from ground at armature 321 and its front contact, opens the circuit for the rotary magnet 312 at armature 349 and its resting contact, and places direct ground on the test wiper 358 at armature 345 and its front contact, and by the same action opens its initial energizing circuit. Relay 308 also prepares a locking circuit for the combina-

tion switch-over and ring-cut-off relay 305 at armature 348 and its front contact, connects the ring-back-tone conductor to the calling line at armature 342 and its front contact to indicate to the calling subscriber that the calling line is being signalled, and it connects up the line wipers 357 and 359 at armatures 343 and 351 in their respective front contacts. By the latter operation, a signalling circuit is established whereby 5 ringing current from conductor FREQ. 3 is intermittently projected over the called line to operate the ringer at the substation B5 to notify the called subscriber that he is wanted. The signalling circuit for the called subscriber is as follows: From the battery connected generator GEN, ringing interrupter RING INT, conductor FREQ. 3 connected to switch jack 3 of the connector, fifth contact 10 of the bank associated with wiper 372, wiper 372, upper winding of the switch-over and ring-cut-off relay 305, armature 336 and its resting contact, armature 328 and its resting contact, armature 343 and its front contact, armature 352 and its resting contact, wiper 357, conductor 373, and the ringer at substation B5, to ground. The above circuit is intermittently opened and closed by the operation of the ringing interrupter RING 15 INT and the ringer at substation B5 is thus operated at intervals to signal the called subscriber. It is understood, of course, that the ringing current also flows through the ringer at substations B1 and B3, shown in Fig. 4, to ground at the same time but the ringers thereat are tuned so that they will not respond to the frequency of ringing current which is now in use. This is in accordance with the well known practice of harmonic signalling, and it follows that the ringer at 20 substation B5 is the only one which is operated.

When the called subscriber at substation B5 removes his receiver to answer the call, the ringer thereat is disconnected and the ringing circuit is completed over a circuit including the other line conductor 375, wiper 359, armature 355 and its resting contact, armature 351 and its front contact, armature 331 and its resting contact, armature 337 and its resting contact, to ground. The combination switch-over and ring-cut-off relay 305 energizes over this circuit closing a locking circuit for itself at its lightly adjusted armature 329 and its front contact, from ground at armature 348 and its front contact, through the lower winding of relay 305 to battery. Relay 305 also opens its original energizing circuit at armatures 328 and 331 and their respective resting contacts and at the same time completes a talking connection at their respective front contacts, and by the same action disconnecting the ring-back-tone conductor from the upper line conductor 141. The release of the apparatus 25

used in establishing the connection is the same as has been hereinbefore described.

An explanation will now be given of the manner in which connections are established with the other four substations on this party line. The substations B1, B2, B3, and B4, as shown in Fig. 4, may be reached by dialing 2134, 2234, 2334 and 2434, respectively. It will be noted that the first, third, and fourth digits of the telephone numbers are exactly the same as used in calling substations B5-B10, inclusive.

When the digit 1 is dialled as the second digit of the telephone number the auxiliary switch AS positions its wipers 371 and 372 to the first contacts of its associated banks which transmits FREQ. 1 over the line conductor 373 to operate the ringer at substation B1. If the digit 3 is dialled as the second digit the auxiliary switch AS will position its wipers 371 and 372 to the third bank contact, and in this case FREQ. 2 is transmitted over the line conductor 373 to substation B3.

If the second digit of the called number is either 2 or 4 the wipers 371 and 372 of the auxiliary switch AS will be advanced to the second or fourth contacts of their associated bank. The circuit for the combination switch-over and ring-cut-off relay 305 will then include the lower winding of the reversing relay 306 over the following circuit: Battery, lower winding of relay 305, contacts 327 of the vertical off-normal springs VON, armature 326 and its resting contact, wiper 371 of the auxiliary switch AS, and the second or fourth contact of its associated bank contact, lower winding of the reversing relay 306, armature 321 and its front contact, to ground. Relays 305 and 306 energize over this circuit. Relay 306 upon energizing, closes a locking circuit for itself from battery, resistance 366, armature 333 and its front contact, lower winding of relay 306, armature 321 and its front contact, to ground and at armatures 336 and 337 and their respective front contacts it prepares a circuit for transmitting FREQ. 1 or FREQ. 2 over the lower line conductor 375 through the ringer of substations B2 or B4.

When ten party service is desired, the same group of connectors serving the five-party lines, shown in Fig. 4, may be used for selectively signalling the subscribers connected to the ten-party line shown in Fig. 5. One of the frequency selecting connectors of the group is the connector C1 shown in Fig. 3 and the different ringing generators are connected to the switch jack terminals of the connector as shown to the left of Fig. 5. By multiplying the party line conductors to two sets of bank contacts accessible to the two sets of wipers of the connector C1, the subscribers C1-C5 are selec- 120 125 130

tively signalled when the normally connected set of wipers of the connector are associated with the bank contacts to which the conductors 573-575 are connected and the subscribers C6-C10 are selectively signalled when the normally disconnected set of wipers of the connector are associated with the bank contacts to which the conductors 563-565 are connected. The signalling of a particular subscriber on the line is exactly the same as has been explained in connection with Fig. 4.

When three party service is desired, a group of frequency selecting connectors, (similar to the connector C1), having the different ringing current generator leads wired to the switch jack terminals, as shown to the left of Fig. 6, are used. It will be noted that only three different ringing frequencies are required for selectively signalling the parties of the two three-party lines shown in Fig. 6. The telephone members of the connected subscribers are the same except for the second digit of the number which selects the ringing frequency, the set of wipers, and the side of the line over which the ringing current is to be transmitted.

It is assumed that the frequency selecting connector C1 shown in Fig. 3, is one of a group of connectors having the switch jack terminals wired as shown to the left of Fig. 6, and that the second digit of the called number is 1, 3, or 5. In response to the dialling of any of these digits as the second digit of the called number the wipers 371 and 372 of the auxiliary switch AS are advanced to contacts 1, 3, or 5 of their associated banks. With the auxiliary switch wipers on any one of these contacts the normally connected set of wipers 357-359 of the connector C1 are used and the ringing frequency (FREQ. 1, FREQ. 2, or FREQ. 3) selected by wiper 372 of the auxiliary switch AS is transmitted to subscriber D1, D3, or D5 over the following circuit: battery connected generator GEN, ringing interrupter RING INT., conductor FREQ. 1, 2, or 3 connected to switch jack 1, 2 or 3, respectively, wiper 372 of the auxiliary switch AS and its associated bank contact 1, 3, or 5, upper winding of the combination switch-over and ring-cut-off relay 305, armature 336 and its resting contact, armature 328 and its resting contact, armature 343 and its front contact, armature 352 and its resting contact, wiper 357, conductor 673 (Fig. 6), ringer of substation D1, D3, or D5 (depending on the selected ringing frequency) conductor 675, wiper 359, armature 355 and its resting contact, armature 351 and its front contact, armatures 331 and 337 and their respective resting contacts, to ground. The above circuit is intermittently opened and closed by the operation of the ringing interrupter RING INT. and the ringer at the selected substation is operated at intervals

to signal the called subscriber. It is understood, of course, that the ringing current also flows through the ringers at the other substations on the line, but the ringers thereat are tuned so they will not respond to the frequency of the ringing current which is now in use. This is according to the well-known practice of harmonic signalling, and it follows that the ringer at the selected substation is the only one which is operated.

When the called subscriber responds to the ringing of his bell by removing his receiver, a direct current bridge is closed across the associated line conductors 673 and 675 in the regular manner, whereupon the ring-cut-off relay 305 energizes. The operation of the circuit following the energization of the combination switch-over and ring-cut-off relay 305 is exactly the same as has been hereinbefore described.

In order to establish a connection with subscribers D6, D8, or D10, connected to the other three-party line shown in Fig. 6, and whose ringers are bridged across conductors 663 and 665, the second digit of the called number is either 6, 8, or 0. The first, third, and fourth digits of the telephone number are the same as used in establishing a connection with subscribers D1, D3, or D5. The wipers 357-362 of the modified connector C1 are connected to the conductors 663-665 and 673-675, shown in Fig. 6 over their associated bank contacts and the wipers 371 and 372 of the auxiliary switch AS are advanced to contacts 6, 8, or 10 of their associated banks by the second digit of the called number. With the auxiliary switch wipers 371 and 372 on any one of these contacts the reversing relay 306 and the wiper switching relay 309 of the connector C1 will be energized. With the wiper switching relay 309 energized the normally disconnected set of wipers 360-362 is used for completing the connection over conductors 663-665 to subscribers D6, D8, or D10. The selected ringing frequency FREQ. 1, 2, or 3 is transmitted to subscribers D6, D8, or D10, over the following circuit: battery connected generator GEN, interrupter RING INT., conductor FREQ. 3, 2, or 1, connected to switch jack 3, 4, or 5, respectively, wiper 372 of the auxiliary switch AS and its associated bank contact 6, 8, or 10, upper winding of the combination switch-over and ring-cut-off relay 305, armature 336 and its front contact (relay 306 having been energized over wiper 372 and contact 6, 8, or 10 of its associated bank), armature 331 and its resting contact, armatures 351 and 355 and their associated front contacts, wiper 362, conductor 665 (Fig. 6), ringer at substations D6, D8, or D10 (depending on the selected ringing frequency), conductor 663, wiper 360, armatures 352 and 343 and their respective front contacts, armature 328 and its resting contact,

tact, armature 337 and its front contact, to ground. The ringer at the selected substation is tuned to respond to a particular ringing frequency.

5 When the called subscriber responds to the ringing of his bell by removing his receiver, a direct current bridge is closed across the associated line conductors 363 and 365 in the regular manner, whereupon the ring-cut-off relay 305 energizes. The operation of the circuit following the energization of the combination switch-over and ring-cut-off relay 305 is exactly the same as has been hereinbefore described.

15 It should be noted that the digit of the number for calling subscribers D1, D3, D8, and D10 can be either digit 1 or 2 for subscriber D1, digit 3 or 4 for subscriber D3, digit 7 or 8 for subscriber D8, and digit 9 or 0 for subscriber B-10. In case the digit 2 or 4 is dialled the ring reversing relay 306 is operated over the second or fourth bank contact of the auxiliary switch AS. The same subscriber, D1 or D3, is signalled by the same ringing frequency as in the case when digit 1 or 3 was dialled, however, the ringing current is now transmitted over the opposite line conductor and back to ground at armature 337 of the reversing relay 306. 20 The ringer at the wanted subscriber's station responds and the connection is completed as before. In case the digit 7 or 9 is dialled the ring-reversing relay is not operated, as is the case when digits 6, 8, or 0 are dialled as the second digit, however, the wiper switching relay 309 is operated as before over the seventh and ninth bank contacts of the auxiliary switch AS. The same subscriber, D8 or D10, is signalled by the same ringing frequency as in the case when digit 8 or 0 was dialled, however, ringing current is transmitted over the opposite line conductors. The ringer at the wanted subscriber's station responds and the conversation is completed in the regular manner.

45 The same group of frequency selecting connectors serving the two three-party lines in Figs. 6 can also be used for establishing connections with five-party lines, such as the two five-party lines shown in Fig. 7. It is assumed that the frequency selecting connector C1 shown in Fig. 3, is one of a group of connectors having the switch jack terminals wired as shown to the left of Fig. 7. It will 50 be noted that three different ringing frequencies are wired to the switch jack terminals in the same manner in Figs. 6 and 7, therefore, the same group of connectors may be used for establishing connection with subscribers connected to three or five party lines. The telephone number of the subscribers connected to the two five-party lines shown in Fig. 7 is the same except for the second digit of the number which selects the ringing 55 frequency, the set of wipers, and the side of

the line over which ringing current is to be transmitted.

The signalling of subscribers E1-E10, inclusive, shown in Fig. 7, is the same as described for signalling subscribers B1-B10, inclusive, shown in Fig. 4, except that the ringing frequencies used for signalling subscribers E1-E5, inclusive, are the same as used for signalling subscribers E6-E10, inclusive. This is made possible by the multiplying of the first two ringing frequencies, FREQ. 1 and FREQ. 2, at switch jacks 1 and 2 of the connector with switch jacks 5 and 4, respectively.

70 What is claimed is:

1. In an automatic switch, a line relay, a release relay, a series relay, two windings of different resistances for each of said last two relays, contacts on said line relay for closing a circuit when said line relay is operated, said circuit including the low and high resistance windings of said release relay and one winding of said series relay in series, self locking contacts on said release relay for closing a locking circuit for maintaining said release relay operated, other contacts for closing a circuit to the other winding of said series relay in series with said low resistance winding of said release relay to operate said series relay, and contacts on said line relay for completing a shunt circuit around the high resistance winding of said release relay to make it slow to release whereby said release relay operates the first time said line relay is energized and remains operated during successive operations of said line relay.

4. In an automatic switch, a line relay, a double wound release relay, a double wound change-over relay, a circuit for operating said line relay, a first circuit for operating said release relay over both of its windings in series with one winding of said change-over relay, a second circuit for operating said change-over relay over both its windings in series with one winding of said release relay, a fourth circuit for shunting one winding of said release relay when said line relay momentarily falls back, contacts on said line relay for opening the circuit of one winding of said change-over relay, current flow in said release and change-over relays being sufficient to maintain said relays in an energized position during the momentary interruptions of said line relay, and off-normal springs operated if said switch is off-normal to prevent said first circuit from being completed.
5. In an automatic switch, a line relay, a release relay having two windings, a series relay having two windings, a circuit for operating said line relay, a first circuit for operating said release relay over both of its windings in series with one winding of said series relay when said line relay is operated, a second circuit for operating said series relay over a second winding of said series relay in series with one winding of said release relay and for making said release relay slow-to-release when said line relay has momentarily deenergized, and a third circuit for operating said release relay over said first circuit and for making said series relay slow-to-release over a circuit including both windings of said release relay in series with the other winding of said series relay when said line relay is again operated.
6. In an automatic switch, a wiper-switching relay, a two-step relay operated through its first step to close a locking circuit for itself which operates the relay through its second step when its initial energizing circuit is opened, contacts on said second relay for preparing a circuit to said wiper switching relay, a normally connected set of wipers and a normally disconnected set of wipers, and contacts on said wiper-switching relay for disconnecting the normally connected set of wipers and for connecting the normally disconnected set of wipers when said relay is operated.
7. In an automatic telephone system, an impulsive device, an automatic switch operative responsive to a plurality of series of impulses transmitted by said impulsive device, a two-step relay operated through its first step by the first impulse of the first series, contacts on said relay for operating it through its second step when said first impulse of said first series is terminated, a normally connected set of wipers and a normally disconnected set of wipers, and a wiper-switching relay operated by the second im-
- pulse of the first series to connect the normally disconnected set of wipers.
8. In an automatic switch, a two-step busy test relay, a first circuit for operating said relay through its first step to close one pair of its contacts when said switch encounters a busy line, and means for operating said relay through its second step over a circuit including said pair of contacts and the busy line when its initial energizing circuit is opened.
9. In a connector, a test wiper, a two-step busy-test relay, a circuit including said test wiper for operating said relay in its first step, and a circuit including said test wiper and contacts closed by the relay in its first step for operating the relay in its second step.
10. In combination, a connector switch, a plurality of sets of wipers, an auxiliary switch individual to said connector switch, means for controlling said auxiliary switch, a plurality of signalling currents, and wipers controlled by said auxiliary switch for selecting a particular one of said signalling currents, one of said plurality of sets of wipers, and the side of the line over which said signalling current is to be transmitted.
11. In a switching device having a plurality of sets of wipers for extending connections to party lines, means for selecting a particular set of wipers and the signalling current for signalling a particular party on a line and for thereafter selecting the desired line, and a relay controlled by said first selecting means for determining over which side of the line the signalling current is to be transmitted.
12. In a telephone system, a connector switch having a plurality of sets of wipers, each set of wipers having access to a plurality of party lines, an auxiliary switch individual to said connector, a plurality of sources of ringing current, means controlled by said connector for operating said auxiliary switch to select a particular one of said sources of ringing current, the set of wipers, and the side of the line over which the ringing current is to be transmitted, and means for thereafter connecting said wipers to a desired line.
13. In a telephone system, a plurality of lines, a connector having a plurality of sets of wipers, an auxiliary switch individual to said connector, a plurality of sources of ringing current, means for positioning said auxiliary switch and for subsequently positioning said connector to select one of said lines, and means controlled by said auxiliary switch for selecting one of said sets of wipers, one of said sources of ringing current and the side of the line over which the ringing current is to be transmitted.
14. In an automatic telephone system, two party lines, a connector switch having a normally connected set of wipers and a normally disconnected set of wipers, means in said con-

5 nector for selectively signalling the subscribers connected to one of the party lines when the normally connected set of wipers is used or for selectively signalling subscribers connected to the other party line when the normally disconnected set of wipers is used.

10 15. In an automatic telephone system, a party line, a switch having a normally connected and a normally disconnected set of 10 wipers, said party line being accessible over either of said sets of wipers when the switch is in a particular position, and means for selectively signalling certain of the subscribers connected to said party line when the normally connected set of wipers are used and for selectively signalling certain other of the subscribers when the normally disconnected set of wipers are used.

15 20. In an automatic telephone system, a first and second party line, a connector switch having access to said party lines over a first and second set of wipers, respectively, means for selecting either of said sets of wipers, means for associating said sets of wipers with said party lines, and means in said connector switch for selectively signalling subscribers connected to the first party line when the first set of wipers has been selected and for selectively signalling subscribers connected to the second party line when the second set of wipers has been selected.

release of said line relay for short circuiting one winding of said release relay and for maintaining a circuit for the other winding of said release relay to make it slow to release.

In witness whereof, I hereunto subscribe my name this 19th day of January, A. D. 1931.

VICTOR S. THARP.
